KNITTING MACHINE WITH RECTILINEAR
NEEDLE BEDS

Michel Cavero, Oloron, France, assignor to Societe en nom Collectif: Lebocey Freres, dite Etablissements Lebocey, Troyes, (Aube) France

Application May 21, 1935, Serial No. 22,606
In France May 25, 1934

3 Claims. (Cl. 66—76)

This invention relates to a knitting machine, provided with a rectilinear needle bed, and more particularly adapted for the manufacture of berets, although it also allows of producing fancy articles. This knitting machine is essentially characterized by the fact that:

(a) Contrarily to similar existing knitting machines, the hand control, instead of being of the alternate type, is continuous; the movement thus produced is transformed into rectilinear reciprocating strokes of the carriage relatively to the needle bed, by means of a transmission which is of simple construction, since it is only composed of an endless chain, of a finger secured on this chain and of a vertical slide rigid with the carriage and in which said finger extends.

(b) The decreases or increases are automatically obtained by causing to act, on the needles, push-bars, of variable lengths arranged according to the generatrices of a cylinder having a horizontal axis. It therefore suffices to move this cylinder towards the needles for pushing those adapted to operate, then after releasing, to cause said cylinder to angularly move in order to obtain another decrease or another increase.

(c) In the particular case concerning the manufacture of berets, the cylinder acting on the needles is subjected to similar angular displacements separated by returns to an initial position; these strokes are counted by a pawl and ratchet device which, after stoppage of the cylinder, controls, in its turn, the number of strokes to which the carriage is subjected, with a different thread-thrower and relatively to the needle bed.

The invention is illustrated by way of example, in the accompanying drawings, in which:

Fig. 1 is a side view of the device for controlling the system for effecting the increases and decreases.

Figs. 2 and 3 are an elevation and a cross section, made according to line A—A of Fig. 2, showing the system for driving the knitting cams carriage and the thread-throwers.

Figs. 4 and 5 are a plan view and a vertical section, made according to line B—B of Fig. 4, showing the mechanism controlling the increases and decreases as well as the operation of the thread-throwers.

Fig. 6 is a side view of the mechanism shown in Fig. 4.

Figs. 7 and 8 illustrate the device for braking the drum effecting the increases and decreases.

As illustrated in the accompanying drawings, the knitting machine forming the subject-matter of the invention, comprises a rectilinear needle

bed 1, provided with needles 2. Above this needle bed 1 and parallel thereto is arranged a double guide race 3. The cross section of this guide race is in the shape of a double T, one of the lower branches being bevelled (Fig. 3). Moreover, in the upper face of this guide race is provided a groove 4 also serving as guide for a link 5, the function of which will be indicated later on.

The lower guide race allows rectilinear reciprocating movements of the carriage 6 which carries 10 knitting cams adapted to act on the needles 2 for the formation of the stitches. This carriage 6 is moreover so devised that it can drive either of the carriages 7, 8 carrying the thread-throwers. These carriages 7, 8 are guided by the upper 15 guide race, between abutments 9.

For actuating the thread-throwers, the lower carriage 6, which is held in contact with its guide slide by an adjustable wedge 10, is provided, on its front face, with vertical lugs 11. Between 20 these lugs 11 is pivoted, on a horizontal pin 12, a driving dog 13. This dog 13 has a lower butt, so that it can angularly move only by moving away from the guide race 3. This angular displacement takes place in opposition to the action of 25 springs 14 attached to the carriage 6. In these conditions, this dog 13 will be able to drive or not drive the thread-throwers by coming in engagement with a finger 15 provided on each of said carriages 7 and 8. This finger 15 is curved forwardly and downwardly. Its end has, on either side, bevelled portions forming inclines (Fig. 4). Said fingers are respectively pivoted about a horizontal pin 16 in a transverse mortice of the corresponding carriage 7, 8. They are provided with 30 a lower extension 17 which coincides with the upper groove 4 of the guide race 3. This extension 17 passes through the corresponding carriage 7, 8, through a suitable opening; the lower face of the extension 17 being obliquely cut. 35 Springs 18, attached on the upper face of the carriages 7, 8, act on the fingers 15 for holding them in lowered position.

The driving carriage 6 receives reciprocating rectilinear displacements relatively to the needle bed 1, but the driving control has a continuous movement of rotation in the same direction. The driving mechanism is, for that purpose, constituted as follows (Fig. 2):

A hand wheel actuates, by means of a toothed 50 wheel 19 and a pinion 20, an endless chain 21 stretched between pinions 22, 23.

This chain 21 is arranged parallel to the guide race 3 of the carriage 6. At one point of this chain 21 is laterally mounted a roller 24 provided 55

with cheeks. This roller 24 extends in a vertical groove 25 formed in a vertical plate 26 rigid with the carriage 6. This plate 25 thus forms a slide for the roller 24 and its guide cheeks. In these conditions, the carriage 6 is driven in one direction when the roller 24 moves with the upper stretch of the endless chain 21. At the end of the stroke, the roller 24 moves about the corresponding pinion whilst it lowers in the groove 25. The roller 24 thus comes on to the lower stretch of the endless chain 21, which drives it in the reverse direction at the same time as the adjacent carriage 6. At the end of the stroke, the same operation takes place over again in the reverse direction for restoring the roller 24 to its highest position, on the upper stretch of the driving chain 21.

The knitting machine forming the subject-matter of the present invention has been more particularly devised for automatically forming increases and decreases, as is common practice for the manufacture of Basque berets. With the means already described will therefore be combined other means which will allow of obtaining the desired result and will be described hereinafter.

For moving in the needle bed 1 the needles 2 which must operate or not, use is made of a rotary cylinder 27, the axis of which is parallel to the needle bed 1 and which can also receive displacements moving it towards or from the needles 2. On the periphery of this cylinder 27, and mounted on cross members 28, are provided blades 29 of different lengths, according to the number of needles to be simultaneously operated.

This operation takes place when the cylinder 27 is moved towards the needles 2, the corresponding blade 29 acting as a push-piece for moving said needles 2 in the divisions of the needle bed 1. Above the needle bed 1 there is shown the guide race 3 with the carriages 6, 7 and 8 sliding thereon. The lower carriage 6 carries knitting cams 81 of the construction well known in the art and adapted to cooperate with the shoulders 2' of the needles 2. In the position shown in Fig. 1, the shoulder 2' lies outside the path of the traversing knitting cams 81 which, therefore, do not act upon the needle 2. Only when the needle is pushed forward by the blade 29, the shoulder 2' is brought to cooperate with the cams 81, thereby imparting the knitting movements to the needle 2. According to the different lengths of the blades 29, variable numbers of needles are pushed forward so as to be actuated by engagement of their shoulders 2' with the cams 81.

The movements for bringing the cylinder 27 towards the needles 2 and moving it away therefrom are obtained by mounting the ends of the shaft of said cylinder on two similar levers 39 journaled about a lower shaft 31, which is common thereto. One of these levers carries a roller 32 on which acts a rotary cam 33 (Fig. 1). The shaft of this cam 33 is actuated from the driving transmission of the cam carriage. To the action of the cam is opposed that of a spring 34 tending to restore the cylinder 27 towards the needles 2.

The intermittent rotation of the cylinder 27 is obtained by means of the following mechanism: The cylinder 27 is loosely mounted on the shaft 35 supporting the two angularly movable levers 39. At one of its ends, the cylinder is rigid with a ratchet 36. Two pawls 37, 38 engage with the teeth of this ratchet 36. The pawl 37 is mounted on a plate 39 journaled on the shaft 35 of the

cylinder 27, while the pawl 38 is mounted on the lever 30.

Adjacent to the plate 39 is arranged a second plate 43 carrying the pivot pin of a pawl 44 and formed with two inclines 40, 41 adapted to act upon pins 42 mounted upon the pawls 31, 38 (Figs. 1 and 4). The pawl 44 cooperates with a ratchet 45 loosely mounted on the shaft 35 of the cylinder 27. This ratchet 45 is rigid with a disc 46 carrying two side cams 47, 48, the function of which will be explained later on (Fig. 6).

On the shaft of the cylinder 27 is also carried a pulley 49, to which is attached a cable 50 carrying a freely hanging counterweight 51.

With the cam 48 of the disc 46 engages a contact finger provided on a rocking lever 53 of the third order. The free end of this lever 53 extends between two driving abutments 54 provided on the link 5. This link 5, which is subjected, on the other hand, to the action of a spring 55, is arranged in the longitudinal groove 4 formed in the upper part of the guide race 3 of the carriages. The link 5 has two wedges 56 (Fig. 5) which are received in the abutments 9 and can (when the link 5 is moved in the suitable direction) alternately come out of the latter. On each of the upper carriages 7 and 8 is mounted a "thread thrower" 82 (or yarn guide) leading the yarn 83 to the needles. The fingers 13 and 15 are automatically disconnected at the end of each stroke in the following manner: When the carriage 7 (or 8) strikes against the abutment limiting its movement, the finger 13 moving with the lower carriage 6 is pushed back by the beveled edge of the finger 15 (see Fig. 4) against the action of the spring 14 and slides past the finger 15. When the carriage 6 has completed its movement and comes back on the return stroke, the finger 13 engages the other side of the finger 15 and takes the carriage 7 (or 8) along. Of course, the spring 14 must be strong enough to provide for secure driving of the upper carriage 7 (or 8) along the guide track, but it allows the finger 13 to swing back and jump over the finger 15 when the upper carriage is arrested by its abutment. When the carriage 6 brings back the thread-thrower 7 or 8 it drives, in contact with the abutment 9 from which the wedge 56 is released, the catch 17 is lifted. The finger 15 is angularly moved about its axis. The driving dog 13 of the carriage 6 then leaves the thread-thrower against the corresponding abutment 9.

The other cam 47 of the disc 46 acts on an arm 57 mounted on a rocking lever 58. This lever 58 is pivoted on a shaft 59 at right angles to that of the blade-carrying cylinder 27, so that its oscillations take place parallel to the latter. A spring 59' holds the arm 57 in contact with the driving cam 47. On this lever 58 is mounted an abutment 60 angularly movable about a shaft 61 parallel to the shaft of the cylinder 27. The downward stroke of this abutment lever 60 is limited by an abutment 62 against which a spring 63 tends to maintain the contact. The said abutment lever 60 terminates in a bevelled portion cooperating with another abutment 64 mounted on the blade-carrying cylinder 27.

These latter arrangements are adapted to allow the counterweight 51 to restore the cylinder 27 to an initial position after it has been subjected to angular displacements of definite amplitudes.

The upper end of the lever 58 is bevelled and is normally located in front of the pawl-carrying plate 39 causing the cylinder 27 to rotate.

On one of the cylinder-carrying levers 30 is

moreover provided an abutment 65 adapted to come in engagement with a catch on the cylinder 27. For this arrangement can be substituted in order to avoid shocks, two cams 66 and 66' (Fig. 7) carried by the cylinder 27 and cooperating with a pivoted braking lever 67 replacing the fixed abutment. This lever 67 is provided with a lug 68 for securing in position a fork-piece 69 terminating a rod 70. This rod 70 is subjected to the action of two springs 71, 72, of different power, bearing on either side of a lug 73 of the frame secured on the lever 30. One of these springs 71 bears on the fork-piece 69, and the other 72 is retained by adjusting nuts 74 screwed 15 on the screw-threaded portion of the rod 70.

The operation of this knitting machine is as follows:

As previously indicated, the carriage 6 receives rectilinear reciprocating movements above the 20 needle bed 1, and actuates either of the thread-throwers 7, 8.

At each end of the stroke, the cam 33 acting on the roller 32 presents to the latter its flat portion, so that the spring 34 angularly moves 25 the two levers 30 carrying the cylinder 27. The cylinder 27, which is prevented from rotating by its pawls 37, 38, brings its blade 29 in contact with the needles 2 and moves, relatively to the needle bed 1, those which are to operate. The 30 number of the latter varies according to the length of the blade 29 carried by the cylinder 27. This consequently allows obtaining the desired increases or decreases.

The cam 33, continuing its movement, moves 35 the levers 30 in reverse direction, so that the plate 39 engages with the rear abutment 58. This plate 39 pivots and actuates the driving pawl 37 which causes the angular displacement of the cylinder 27 and the permutation of the blades 29 40 adapted to act on the needles 2. The other pawl 38 acts as a stop.

This operation takes place over again at each 45 stroke of the carriage 6. When a part of the article is finished, for instance after executing a "palm" in the case of the manufacture of a beret, the abutment 64 carried by the cylinder 27 has come in contact with the bevelled end of the abutment 60. This contact has caused the transverse oscillation of the abutment lever 58. The plate 50 39 no more strikes the lever 58 but the latter has moved in front of the second pawl-carrying plate 43. This plate 43 has, therefore, struck against the lever 58 and the angular displacement to which it has been subjected from this fact, has, 55 by means of the pawl 44, moved the ratchet 45 to the extent of the tooth. This ratchet 45 will, therefore, count the successive "palms" or parts which will be knitted. When the plate 43 is angularly displaced, its inclines 40, 41 act on the 60 pins 42 of the pawls 37, 38 for lifting them from the teeth of the corresponding ratchet 36. The cylinder 27, which has thus been released, is moved backwards, by the counterweight 51, until the abutment 66 of the cylinder 27 stops by 65 engaging with the abutment 65 carried by lever 30. In practice and in order to avoid shocks, the abutment on cylinder 27 is formed by an inclined cam 66 and a stop cam portion 66' (Fig. 7) and cooperates with a resilient braking lever 67, 70 as above described (Fig. 8).

The parts having resumed their initial positions, a new cycle of operation can take place over again.

When the necessary number of palms has been knitted and counted, the cam 47 of the disc 46 comes in engagement with the arm 57. The abutment lever 58 cannot therefore come back in front of the plate 39 carrying the pawls 37, 38 5 actuating the cylinder 27. This lever 58 is, on the other hand held stationary in front of the plate 43 actuating the counting disc 46.

The cam 33, by actuating the levers 30, will therefore at each alternate stroke, angularly move 10 the disc 46 to the extent of one tooth. At the same time, the other cam 48 has pushed the lever 53, and this has caused the link 5 to longitudinally move in the groove of the guide frame 3.

The movement of the wedges 56 has thus re- 15 leased at the end of its stroke the thread-thrower which was primitively moving. The other thread-thrower has, on the contrary, been coupled with the carriage 6 which now drives it in its turn. The movement of this thread-thrower continues 20 during all the time the disc 46 angularly moves, this disc 46 receiving successive displacements until it reaches again its inward position. At the end of the movement, the cams 47, 48 move away 25 from the levers 57 and 53, the stop lever 58 returns therefore to its initial position, as well as the link 55, this ensuring again the permutation of the thread-throwers 7, 8.

I claim:

1. A flat knitting machine, specially for the 30 manufacture of berets and other fancy articles comprising a number of similar parts, having a needle bed, sliding needles on said needle bed, yarn guides reciprocable above said needles, a rotatable cylinder, means for imparting to said cylinder a 35 reciprocating movement towards and away from said needles, means mounted on said cylinder and adapted to push needles from an inoperative into an operative position, a ratchet mounted on said cylinder, a plate pivotally mounted on said cylinder, a pawl mounted on said plate and cooperating with said ratchet, an abutment member pivotally mounted on the machine and adapted to engage and rock said plate at the return stroke of the cylinder so as to advance said ratchet and 40 cylinder by a step, a second pawl preventing backward movement of said ratchet, a second ratchet rotatably mounted on said cylinder, a second plate pivotally mounted on the cylinder, a third pawl mounted on said second plate and engaging said 45 second ratchet, a cam mounted on said cylinder and adapted to shift said abutment member away from said first plate and in the path of the second plate, a spring tending to return said abutment member to its initial position, means on said second plate adapted to release said first and second pawl when said second plate is rocked by said 50 abutment member, and means tending to move said cylinder back to its initial position.

2. A flat knitting machine as claimed in claim 1, 60 comprising a disc mounted on said second ratchet, and a second cam provided on said disc and adapted to retain said abutment member in its shifted position.

3. A flat knitting machine as claimed in claim 1, 65 comprising a disc mounted on said second ratchet, a second cam provided on said disc and adapted to retain said abutment member in its shifted position, means for releasing one of said yarn guides and for actuating another yarn guide, and a third 70 cam provided on said disc and adapted to actuate said last mentioned means.

MICHEL CAVERO.
